Specification of Letters Patent.

Patented Oct. 3, 1916.

Application filed January 12, 1916. Serial No. 71,615.

To all whom it may concern:

Be it known that we, WILLIAM KLOCKE and JOHN E. DOBSON, both citizens of the United States of America, residing in the 5 borough of Brooklyn, county of Kings, in the city and State of New York, and in the borough of Manhattan, city, county, and State of New York, respectively, have invented certain new and useful Improvements in Presses, of which the following is a specification.

This invention relates to a press of the type adapted for the heavier kind of work wherein pressures of two thousand tons or 15 more may be encountered.

The general type of press forming the subject matter of this application is disclosed in the Klocke Patent No. 1,108,187. In the construction of press illustrated in 20 the said patent, the stationary bed is located above the movable plunger and the latter is operated by cranks which push the plunger toward the bed in the working stroke of the punch. The base of the press and the bed 25 are held together by tie rods, and it will be perceived that the entire strain incident upon the operation of the press comes upon the tie rods. This necessitates that the tie rods shall be of great strength and that the 30 nuts and connections between the tie rods and the parts to which they are secured shall be likewise of great strength and solidity. Notwithstanding this, the enormous strains encountered in the operation of the press in 35 time will stretch the tie rods.

The object of the present invention is to provide a construction wherein the tie rods shall be entirely relieved from all tensile strain, and this result is accomplished by 40 supporting the bed from the base of the press and causing cranks which are likewise operated from the base of the press to draw the plunger toward the bed. Thereby all tensile strain will be removed from the tie 45 rods and the only strain to which they will be subjected will be a compressive strain between the bed and the base of the machine.

A desirable form in which our invention may be embodied is illustrated in the accompanying drawings, wherein—

Figure 1 is a side view, partly in section, of a press constructed according to our invention; Fig. 2 is an end view thereof from the left-hand end, Fig. 1, partly broken, and

Fig. 3 is a section on the line 3—3, Fig. 1, 55 looking in the direction of the arrow.

The press in connection with which we have illustrated our invention is provided with a base or bottom A, a stationary bed B, and a movable plunger C. The stationary 60 bed is supported on the base A by stay rods D, of which a suitable number may be provided. The machine is illustrated as having four of such stay rods on each side of the machine. These stay rods pass through lugs 65 b on the bed B, and have nuts d threaded thereon, by which the bed is supported, and which are adjustable to permit the bed to be supported in the desired position, and which serve to resist the downward strain of the 70 table B and to transfer to the stay rods D compressive strains between the base A and bed B. The upper ends d¹ of the tie rods D pass through holes in lugs c on the plunger C, and serve to guide the plunger in its 75 movements. Fig. 3 illustrates a die block E upon the bed B, and a punch F upon the plunger C, and the punch in this figure is illustrated as drawing the work G down into the die block.

In the base A of the machine is mounted a crank shaft H having thereon a crank I, the connecting rod J of which is connected to the plunger C and tends to draw the same down toward the bed in its operative movement. Four of such crank shafts are illustrated as being provided, two on each side, and each is illustrated as carrying one crank and operating one connecting rod, but obviously any desired number of such crank 85 shafts, cranks and connecting rods may be employed.

The stay rods D are keyed to the base A by keys K (Fig. 3), but are free at their upper ends. A knockout L may be employed, if desired, to remove the blank from the die blocks E. Any desired number of such knockouts may be employed, according to the length of the bed of the press. Each is illustrated as mounted upon a bar 100 M hung by rods m, m¹ from the plunger C. The rods m, m¹ are threaded in the bar M and at their upper ends have worm gears m² which provide the desired adjustment for the knockouts through worms on the 105 adjusting shaft N. Any other knockout desired may be employed, as the invention is not concerned with this feature.

The crank shafts H are driven from a driving shaft O having a pinion o which meshes in gear P¹ on shaft P, upon which is a pinion p meshing in gear Q¹ on shaft 5 Q. This shaft has pinions q which mesh in the crank shaft gears H¹ on the crank shafts H. The main driving shaft Q extends throughout the length of the machine, and has thereon as many pinions q as there are 10 crank shafts to be driven. This main driving shaft extends down through approximately the center of the base of the machine, and the pinion q thereon each engage two crank shaft driving gears H¹ on opposite 15 sides of the machine.

The other crank shafts H, gears H¹ and connecting rods J are similarly constructed to those described, and accordingly the same letters of reference are used for the corresponding parts.

We have illustrated the most desirable form of constructing our invention now known to us, but the same may be modified and equivalent devices substituted for those 25 illustrated, within the limits of the appended claims, without departing from the spirit of the invention.

We do not intend to be limited to the precise construction of press illustrated, nor 30 to the precise number of parts.

What we claim is:—

1. In a power press for heavy work, a base, a movable plunger, and a stationary bed between said parts, stay rods connecting the base and bed and forming guides for the plunger, a crank shaft mounted in the base, and cranks thereon adapted to draw the plunger to its work.

2. In a press of the character described, 40 a lower stationary bed and an upper plunger movable toward and from said bed, stay rods connected to the frame of the press and providing a support for said bed and

guiding said plunger, a crank shaft mounted in the frame below said bed, and cranks thereon adapted to draw the plunger to its work.

3. In a power press for heavy work, an upper movable plunger, a stationary bed below said plunger, connections between the 50 base of the machine and the bed, a crank shaft mounted in the base, and cranks thereon adapted to draw the plunger to its work.

4. In a power press for heavy work, a base, an upper movable plunger and a stationary bed below said plunger, rods attached to the base and supporting said bed, and extending beyond said bed to provide guides for the plunger, crank shafts mounted in the base, and a plurality of cranks 60 thereon adapted to draw the plunger to its work.

5. In a power press for heavy work, a base, an upper movable plunger and a stationary bed below said plunger, rods attached to the base and supporting said bed, crank shafts mounted in the base on each side of the press, and a plurality of cranks 65 on said shaft adapted to draw the plunger to its work.

6. In a power press for heavy work, a base, an upper movable plunger and a stationary bed below said plunger, rods attached to the base and supporting said bed, a crank shaft mounted in the base and a 75 plurality of cranks on said shaft adapted to draw the plunger to its work.

In witness whereof, we have hereunto signed our names in the presence of two subscribing witnesses.

WILLIAM KLOCKE.
JOHN E. DOBSON.
